UNITED STATES PATENT OFFICE.

FRANKLIN A. ERRINGTON, OF STAPLETON, NEW YORK.

CEILING DRILL-PRESS.

1,226,487.

Specification of Letters Patent.

Patented May 15, 1917.

Application filed January 4, 1916. Serial No. 70,281.

To all whom it may concern:

Be it known that I, FRANKLIN ALFRED ERRINGTON, a citizen of the United States of America, residing at Stapleton, borough 5 and county of Richmond, city and State of New York, have invented certain new and useful Improvements in Ceiling Drill-Presses, of which the following is a specification.

10 This invention relates to an inverted drill press for the purpose of drilling, tapping, stud-setting, etc., in all classes of overhead work, such as between decks in ships, in steel beams of buildings, etc.

15 The main object of this invention is to keep the motor and the weight of the outfit as close to the base as possible, thereby making the machine practical for the sensitive operation of tapping; whereas, all previous devices have carried the motor so 20 high, or in such a position as to cause such excessive vibration, as to be unfit for, and cause breakage of taps when attempting to use such an outfit for tapping; moreover, 25 my machine has a double-feed control, as a tap must be controlled while being fed in, and also while being backed out; and my invention further consists in the embodying in a compact and novel structure all the 30 constant elements required in such operations, as will be more fully hereinafter set forth, and then pointed out in the claims.

35 Reference is to be had to the accompanying drawings, forming part hereof, where-
in:

Figure 1 represents a vertical cross-section of a machine embodying my invention; Fig. 2 is a horizontal cross-section of Fig. 1 showing the gear-box in section on the line 40 2-2 on Fig. 1, and illustrating the feed mechanism with its duplex control, and a ratchet to check the downward movement of the rack-sleeve.

Similar numerals and letters of reference 45 indicate corresponding parts in the several views.

A base 1 is provided with uprights 2, 3, 4, 5 that rigidly support a gear-box 6 at a suitable distance above the base 1 to permit 50 the interposition of a motor 7 provided with

a rotary-driving sleeve 8. The gear-box 6 is provided with a main-bearing 6^a in line with said rotary-driving sleeve 8 and adapted to receive a rack-sleeve 9, longitudinally movable in said main bearing 6^a, and held 55 from rotation therein by its rack-teeth intermeshing with the teeth of a feed-gear 10 connected to rotate with a feed-shaft 11, journaled in said gear-box 6 at right angles to the line of travel of said rack-sleeve 9. 60 A spindle 12 is journaled in rack-sleeve 9 and suitably secured to be moved longitudinally in unison therewith,—say by an enlarged tool-carrying end 12^a bearing upon one end of said rack-sleeve, and lock-nuts 65 12^b bearing upon the other end thereof. The other end 12^c of spindle 12 is shown telescoping into the rotary-driving sleeve 8 and rotary-driven thereby through the usual groove in spindle 12 and a key in sleeve 8, 70 or any suitable slip-joint connection.

On one side of gear-box 6 I have mounted a pinion 13 keyed to feed-shaft 11 and adapted to engage a ratchet 14, suitably carried by the framework of the machine and 75 adapted to check the downward movement of the spindle 12, while leaving it free to be fed upward. On the other side of gear-box 6 I have keyed to the other end of feed-shaft 11 another feed-gear 15, adapted to 80 engage the teeth cut in the end of a double-acting spring-clutch 16, journaled in a swing-joint 17, into which I have screwed a hollow feed-handle 18, up the hollow of which I have run a rod 19 to connect a pull- 85 knob 20 with the spring-catch 16. A slot 18^a permits a pin 20^a to sink into the handle 18 far enough to permit the spring-clutch 16 to engage the feed-gear 15 to enable handle 18 to move the rack-sleeve 9 and its 90 spindle 12 up or down as desired. The ratchet 14 holds the spindle 12 in place while the pin 20^a is withdrawn from slot 18^a and pull-knob 20 has been rotated, to uncouple the spring-clutch 16 from gear 15. 95 The handle 18 can then be moved up or down by the operator (independently of feed-gear 15 and the feed mechanism generally), and thereby raise or lower the spindle 12 throughout its entire longitudinal range of 100

travel, by taking a fresh grip on feed-gear 15 whenever any single grip has been exhausted.

It will be seen that one of the uprights, 5, is extended above the gear-box 6 to provide a supporting column for the reverse rod 21 of a suitable reverse-gear box or attachment 22, which may be attached to spindle 12 whenever it is desired to tap with 10 my machine. The column 5 is also useful as a lever or handle when tipping the machine to one side to bring the truck-wheels 23 in contact with the floor to run the machine therealong from place to place where 15 the work is to be performed. When the base 1 stands flat on the floor, the truck-wheels 23 are raised clear of the floor, so that the base rests rigidly thereupon.

The operation of the machine is as follows:—

20 Current is supplied to the motor by any suitable or usual means, a drill (of any suitable length) is placed in the socket 22^a of the reversible spindle of the reverse-gear box or tapping attachment 22, the handle 18 is then lowered, to raise the drill up until it presses firmly against the center-punch or other suitable location to be drilled, whereupon the operator pushes a suitably 25 arranged switch to start the motor 7, which rotates spindle 12 and the drill that is driven thereby. Continued pressure on handle 18 feeds the drill into the work operated upon until the desired depth is attained, 30 when the operator throws out the ratchet 14 before raising the handle 18; the handle 18 is then raised and the drill can be withdrawn, although it is advisable to switch off the motor before withdrawing the drill 35 from the support of the hole in the work, especially when using a long extension drill-shaft. The drill is then taken out, and a tap 24 substituted in its place in socket 22^a, the motor is switched on, and the tap is fed 40 into the hole thus prepared, the ratchet 14 being kept off during the entire tapping operation. When the tap has reached the depth desired, the handle 18 is raised, whereupon the spindle 22^a is operated in the 45 reverse direction to spindle 12 by suitable mechanism in reverse-gear box 22, and the tap is backed out of the work.

Having now described my invention, what I claim is:—

55 1. The combination with a portable base and a motor mounted thereon and provided with a rotary-driving sleeve, of a gear-box rigidly supported at a constant distance above said base and provided with a main bearing extending in line with said rotary-driving sleeve, a non-rotative rack-sleeve longitudinally movable in said main-bearing, its rack meshing with a feed-gear suitably journaled in said gear-box at right angles to the line of travel of said rack-sleeve,

means to rotate said feed-gear to move said rack-sleeve longitudinally in said main-bearing, and a rotary-driven longitudinally movable spindle extending in line with the axis of the motor, one portion of the spindle being suitably journaled in said rack-sleeve to move longitudinally in unison therewith along the main-bearing of the gear-box, the lower portion of the spindle being connected by a slip-joint with the rotary-driving sleeve to be driven thereby and longitudinally movable therealong, and the upper end of the spindle being adapted to receive a tool or tool-holder, substantially as described. 75

2. The combination with a portable base and a motor mounted thereon and provided with a rotary-driving sleeve, of a gear-box rigidly supported at a constant distance above said base and provided with a main bearing extending in line with said rotary-driving sleeve, a non-rotative rack-sleeve longitudinally movable in said main-bearing, its rack meshing with a feed-gear connected to rotate with a feed-shaft journaled 80 in said gear-box at right angles to the line of travel of said rack-sleeve, means to rotate said feed-gear to move said rack-sleeve down toward or up away from said base, a ratchet to check the downward movement 85 while permitting the upward movement of said rack-sleeve, and a rotary-driven longitudinally movable spindle extending in line with the axis of the motor, one portion of the spindle being suitably journaled in 90 said rack-sleeve to move longitudinally in unison therewith along the main-bearing of the gear-box, the lower portion of the spindle being connected by a slip-joint with the rotary-driving sleeve to be driven thereby and longitudinally movable therealong, the upper end of the spindle being adapted to receive a tool or tool-holder, substantially 95 as described. 100

3. The combination with a portable base and a motor mounted thereon and provided with a rotary-driving sleeve, of a plurality of uprights extending above the base to rigidly support a gear-box at a constant distance thereabove, said gear-box being provided with a main-bearing in line with said rotary-driving sleeve, a non-rotative rack-sleeve longitudinally movable in the main-bearing, its rack meshing with a feed-gear mounted upon and connected to rotate with 110 a feed-shaft journaled in the gear-box at right angles to the line of travel of the rack-sleeve, means to rotate the feed-gear to move the rack-sleeve along the main-bearing, and a rotary-driven longitudinally movable spindle extending in line with the axis of the motor, one portion of the spindle being suitably journaled in the rack-sleeve to move longitudinally in unison therewith along the main-bearing, the lower portion of the spin- 115 120 125 130

dle being connected by a slip-joint with said rotary-driving sleeve to turn therewith and slide therealong, the upper end of the spindle being adapted to receive a tool or 5 holder, one of said uprights being extended sufficiently above the gear-box to provide a supporting-column to receive the reverse-

rod of a suitable reverse-gear box carried by said spindle, substantially as described.
